(57) **CLAIM**

The ornamental design for a putter grip, as shown and described.

DESCRIPTION

FIG. 1 is a perspective view of a putter grip showing our new design.

FIG. 2 is another perspective view thereof.

FIG. 3 is a front view thereof.

FIG. 4 is a rear view thereof.

FIG. 5 is a top view thereof.

FIG. 6 is a bottom view thereof.

FIG. 7 is a left side view thereof; and,

FIG. 8 is a right side thereof.

The broken lines shown herein are for illustrative purposes only and form no part of the claimed design.

1 Claim, 5 Drawing Sheets---
